CIRCUIT BREAKER

Joseph A. Drobney and Albert R. Cellerini,
Beaver, Pa., assignors to Westinghouse Electric
Corporation, East Pittsburgh, Pa., a corpora-
tion of Pennsylvania

Application October 6, 1951, Serial No. 250,134

14 Claims. (Cl. 200—88)

1

This invention relates to circuit breakers, and more particularly to circuit breakers for controlling lighting and moderate power circuits.

An object of the invention is to provide a circuit breaker having a switch member biased open and an operating handle supporting the switch member in closed position against its bias.

Another object of the invention is to provide a circuit breaker having an operating handle and a switch member biased open and a support member on said switch member releasably engaging the handle.

A further object of the invention is to provide a circuit breaker having an operating handle, a switch member biased open, a support member between the handle and the switch member and trip means for disengaging the support member from said handle to effect opening of the breaker.

Another object of the invention is to provide a small compact circuit breaker that is simple in construction, reliable in operation and inexpensive to manufacture.

The novel features that are considered characteristic of the invention are set forth in particular in the appended claims. The invention itself, both as to construction and operation, together with additional objects and advantages thereof, will be best understood from the following detailed description thereof when read in conjunction with the accompanying drawing.

In said drawing:

Figure 1 is a side elevational view, partly in section and with the cover plate partly broken away, of a circuit breaker in the closed position embodying the principles of the invention.

Fig. 2 is a view similar to Fig. 1 but showing the parts in the tripped open position.

Referring to the drawing, the circuit breaker comprises a casing 11 and a cooperating cover plate 13, a fragment of which is shown in Fig. 1 broken away. A stationary contact 15 is mounted on a conducting strip 17 which extends through an opening in one end wall of the casing 11 and has a terminal connecting screw 19 at its other end. A movable switch member or arm 21 has spaced side members 22 thereon (only one being shown) adjacent one end thereof through which extends a pin 23. The ends of the pin 23 extend into companion slots 25 (only one being shown) in the side wall of the casing 11 and in the cover plate 13. The switch arm 21 at its outer end carries a movable contact 27 for cooperating with the stationary contact 15. The switch arm 21 is biased open by means of a spring 29 compressed between a spring seat 28 in the base of the cas-

ing 11 and a spring guide 30 on the switch arm 21.

An operating handle 31 of molded insulating material is pivotally mounted on a pin 33 supported in suitable bearing openings (not shown) in the side wall of the casing 11 and in the cover plate 13. The handle 31 extends outwardly through an opening 37 in the casing 11 and substantially closes the opening in all positions of the handle. The inner end of the handle 31 is provided with a projection 39 having a slightly concave surface 41 which, in the closed position of the breaker, engages the rounded upper end of a support member 43, the other end of which is pivotally connected by means of a pivot pin 45 to the side members 22 of the switch arm 21. A relatively light spring 47 compressed between a spring seat 49 in the casing 11 and the support member 43 biases the support member counterclockwise about the pivot 45 against a projection 51 on the casing 11 in which position the point of contact 39—41 of the handle 31 and the support member 43 is substantially in line with the pivots 33 and 45, respectively, of the handle and the support member, thus holding the switch arm 21 in the closed contact position.

The contacts are opened manually by counterclockwise movement of the operating handle 31 from the "On" position to the "Off" position (indicated by dot and dash lines, Fig. 1). During this movement of the handle 31, the friction between the projection 39 and the end of the support 43 is not sufficient to cause rotation of the support member 43 against the bias of the spring 47. Consequently, the projection 39 is disengaged from the support member 43 permitting the spring 29 to move the switch arm 21 to the open position in which it appears in Fig. 2. During the manual opening movement, the support member 43 moves upwardly to the position indicated by dot and dash lines at 43a (Fig. 1). The opening movement of the switch arm 21 is limited by engagement thereof with a surface 53 on the casing 11 and by engagement of the pin 23 with the upper ends of the slots 25.

The contacts are closed manually by movement of the handle 31 from the "Off" (shown by dot and dash lines in Fig. 1) to the "On" position. It will be seen that in the open position of the breaker the rounded upper end of the support member 43 lies adjacent a cam surface 55 on the handle. Upon clockwise rotation of the handle 31, the cam surface 55 engages and cams the support member 43 downwardly and moves the switch arm 21 to the closed position. The last increment of movement of the

handle brings the concave surface 41 into engagement with the end of the support member 43 which is then biased by the spring 47 to the position shown in Fig. 1 substantially in line with the pivots 33-45 or slightly overset to the left of a line drawn through the centers of the pivots 33-45.

It will be observed that the slots 25 are disposed at a slight angle to provide a wiping action between the contacts as they are closed.

The circuit breaker is opened automatically in response to overload currents by means of a thermally and magnetically responsive trip device indicated generally at 57. The trip device comprises a bimetal element 59 having one end suitably secured, preferably by welding, to the inner end of a conducting strip 61 which extends out through an opening in the end wall of the casing 11 and is provided at its other end with a connecting screw 63. The connected ends of the bimetal element 59 and the conducting strip 61 are seated in a notch in the casing 11 in order to accurately position the trip device.

The bimetal element 59 from a point just below its point of connection with the strip 61 extends inwardly at an angle and the free end of the bimetal element 59 is connected by means of a flexible conductor 65 to the left-hand end of the switch arm 21. Disposed adjacent the free end of the bimetal element 59 is an ear 67 formed on a projection 69 on the support member 43.

Secured to the bimetal element in a suitable manner, for instance, by welding is a resilient member or spring strip 71 having a main body spaced from the bimetal element and extending substantially parallel thereto on the side of the bimetal away from the support member 43. A magnetic member 73 is rigidly secured to the bimetal element 59 and a cooperating magnetic member or armature 75 is mounted on the spring strip 71. An adjusting screw 77 threadedly engaging the free end of the spring strip 71 and locked in place by a lock nut 79 extends through a clearance opening in the bimetal element 59 and has its end disposed adjacent the ear 67.

When an overload current occurs below a predetermined value of, for example, 1000% of normal rated current, the bimetal element 59 becomes heated by the excessive current and when heated a predetermined amount deflects toward the right (Fig. 1) engaging the ear 67 and moving the support member 43 clockwise about its pivot 45 against the bias of the spring 47. During this movement, the handle 31, due to the friction between the surface 41 and the end of the support member 43, rotates counterclockwise. This action continues until the support member 43 escapes from the concave surface 41 whereupon the spring 29 acts to move the switch arm 21 to the open position moving the support member to the position in which it is shown in Fig. 2. After escaping from the surface 41, the upward movement of the support member 43 causes the upper end thereof to engage a projection 31 on the handle 31 and move the latter to an intermediate indicating position shown in Fig. 2 in full lines.

The parts are shown in the tripped open position in Fig. 2. In this position, the spring 47 biases the support member 43 and the handle toward the Fig. 1 position, but since the spring 29 is stronger than the spring 47, the parts will be held in the Fig. 2 position until the handle 31 is moved to the "Reset" position shown in dot and dash lines in Fig. 2. When the handle is

moved to the "Reset" position, it frees the support member 43 which is immediately snapped counterclockwise by the spring 47 to its position against the stop 51. Thereafter the contacts are closed in the previously described manner by movement of the handle 31 clockwise to the "On" position. During this movement the cam surface 55 on the handle engages and cams the support member 43 downwardly to move the switch arm to the closed position.

Upon the occurrence of an overload current above 1000% of normal rated current, or a short circuit current, the electromagnet 73-75 is energized sufficiently to attract the armature 75 and bend the spring strip 71 causing the screw 77 to engage and actuate the support member 43 to thereby effect instantaneous opening of the contacts. Following an instantaneous opening operation, the breaker mechanism is reset and the contacts closed in the previously described manner by first moving the handle 31 counterclockwise to the "Reset" position and then clockwise to the "On" position.

The invention provides a circuit breaker of simple construction and having a minimum number of parts. The circuit breaker is trip free of the operating handle and is provided with a thermally and electromagnetically responsive trip device, the electromagnetic trip being supported entirely on the thermal element.

While the invention has been disclosed in accordance with the provisions of the patent statutes, it is to be understood that various changes in the structural details and arrangement of parts may be made without departing from some of the essential features of the invention.

We claim as our invention:

1. A circuit breaker comprising a movable switch member biased to open position and movable to open and close the circuit, an operating handle movable to an open position and to a closed position, a support member on said movable switch member releasably engaging said handle to maintain said switch member in the closed position, a spring biasing said support member to a normal position relative to said handle, manual movement of said handle to said open position causing release of said support member from said handle to permit opening movement of said switch member, and a trip device responsive to overload currents for engaging and releasing said support member from said handle to permit opening movement of said switch member.

2. A circuit breaker comprising a movable switch member movable to an open position and to a closed position to open and close the circuit, biasing means biasing said switch member to open position, a pivoted operating handle movable to an open position and to a closed position, a support member mounted on said switch member and releasably engaging said handle to maintain said switch member in the closed position, spring means biasing said support member about its mounting on said switch member to a normal position against a fixed stop, said handle when moved to said open position causing release of said support member from said handle to permit said biasing means to move said switch member to open position, and a trip device operable in response to overload currents to engage and release said support member from said handle to effect automatic opening of said switch member.

3. A circuit breaker comprising a movable switch member biased to open position and movable to open and close the circuit, an operating handle movable to an open position and to a closed position, a support member disposed between said handle and said movable switch member normally releasably restraining said switch member in closed position, said support member being released from said handle upon movement of said handle to said open position to permit opening movement of said switch member, and a trip device operable in response to abnormal circuit conditions to engage and move said support member to effect release of said member from said handle to permit opening movement of said switch member.

4. A circuit breaker comprising a movable switch member biased open and movable to open and close the circuit, an operating handle movable to an open position and to a closed position, a pivotal support member disposed between said handle and said movable switch member normally releasably restraining said movable switch member in closed position, movement of said handle to said open position effecting release of said support member from said handle to permit opening movement of said switch member, and a bimetal element heated in response to overload currents and operable when heated a predetermined amount to engage said support member and effect release of said support member from said handle to permit opening movement of said switch member.

5. A circuit breaker comprising a switch member biased open and movable to open and close the circuit, an operating handle movable to an open position and to a closed position, a support member disposed between said handle and said switch member normally releasably restraining said switch member in closed position, movement of said handle to said open position effecting release of said support member from said handle to permit opening movement of said switch member, and a bimetal element heated in response to overload currents and operable when heated a predetermined amount to engage said support member and effect release of said support member from said handle to permit opening movement of said switch member, and a projection on said handle engageable by said support member upon release of said member by said bimetal element and opening movement of said switch member to move said handle to an intermediate indicating position.

6. A circuit breaker comprising a pivoted switch member biased open and movable to open and close the circuit, an operating handle movable to an open position and to a closed position to effect manual opening and closing movement of said switch member, a support member disposed between said handle and said switch member normally releasably restraining said switch member in closed position, stop means limiting the movement of said support member in one direction relative to said handle, spring means biasing said support member against said stop means, a bimetal element having one end supported and the other end free, and thermal bending of said bimetal element causing the free end thereof to engage said support member and release said support member from said handle to permit opening movement of said switch member.

7. A circuit breaker comprising a pivoted switch member biased open and movable to open and close the circuit, an operating handle movable

to an open position and to a closed position to effect manual opening and closing movement of said switch member, a support member disposed between said handle and said pivoted switch member normally releasably restraining said switch member in closed position, stop means limiting the movement of said support member in one direction relative to said handle, spring means biasing said support member against said stop means, a projection on said support member, a bimetal element having one end supported and the other end free, and thermal bending of said bimetal element causing the free end thereof to engage said projection and effect release of said support member from said handle to permit opening movement of said switch member.

8. A circuit breaker comprising a movable switch member biased open and movable to open and close the circuit, an operating handle movable to an open position and to a closed position, a support member pivotally connected to said movable switch member and releasably engaging said handle to restrain said switch member in closed position, and a trip device operable in response to overload currents to engage and release said support member from said handle and permit opening movement of said switch member.

9. A circuit breaker comprising a switch member biased open and movable to open and close the circuit, an operating handle movable to an open position and to a closed position, a support member pivotally connected to said switch member and releasably engaging said handle to restrain said switch member in closed position, and a trip device operable in response to overload currents to engage and release said support member from said handle to permit opening movement of said switch member, and said support member when released by said trip device engaging and moving said handle to an intermediate indicating position.

10. A circuit breaker comprising a switch member biased to open position and movable to open and close the circuit, an operating handle movable to an open position and to a closed position to effect manual opening and closing movement of said switch member, a support member having one end releasably engaging said handle and the other end pivotally engaging said switch member, a trip device comprising a bimetal element having one end supported and the other end free, said bimetal element bending when heated in response to overload currents below a predetermined value to effect release of said one end of said support member from said handle and opening movement of said switch member, and electroresponsive means operable in response to overload currents above said predetermined value to engage and effect release of said one end of said support member and instantaneous opening movement of said switch member.

11. A circuit breaker comprising a switch member biased open and movable to open and close the circuit, an operating handle movable to an open position and to a closed position to effect manual opening and closing movement of said switch member, a support member having one end releasably engaging said handle and the other end pivotally engaging said switch member, a trip device comprising a bimetal element having one end supported and the other end free, said bimetal element bending in response to overload currents below a predetermined value to engage and effect release of said one end of said support member from said handle to permit opening movement of said switch

member, a resilient member having one end supported adjacent the supported end of said bimetal element, electroresponsive means comprising a magnetic member mounted on said bimetal element and an armature mounted on said resilient member, and said electroresponsive means when energized in response to overload currents above said predetermined value bending said resilient member and causing said resilient member to engage and release said support member from said handle to effect instantaneous opening movement of said switch member.

12. A circuit breaker comprising a switch member biased open and movable to open and close the circuit, an operating handle movable to an open and to a closed position to effect manual opening and closing movement of said switch member, a support member having one end releasably engaging said switch member, said support member having a projection thereon, a trip device comprising a bimetal element having one end supported and the other end free, said bimetal element bending in response to overload currents below a predetermined value to engage said projection and release said support member from said handle to permit opening movement of said switch member, a resilient member having one end supported adjacent the supported end of said bimetal element and the other end free, an adjusting screw on the free end of said resilient member, electromagnetic means comprising a first magnetic member on said bimetal element and a second magnetic member on said resilient member, said electromagnetic means when energized by overload currents above said predetermined value bending said resilient member and causing said adjusting screw to engage said projection and instantaneously release said support member from said handle.

13. A circuit breaker comprising a switch member biased open and movable to open and close the circuit, an operating handle movable to an open and to a closed position to effect manual opening and closing movement of said switch member, a support member having one end releasably engaging said switch member, said support member having a projection thereon, a trip device comprising a bimetal element having one

end supported and the other end free, said bimetal element bending in response to overload currents below a predetermined value to engage said projection and release said support member from said handle to permit opening movement of said switch member, a resilient member having one end supported adjacent the supported end of said bimetal element and the other end free, an adjusting screw on the free end of said resilient member, electromagnetic means comprising a first magnetic member on said bimetal element and a second magnetic member on said resilient member, said electromagnetic means when energized by overload currents above said predetermined value bending said resilient member and causing said adjusting screw to engage said projection and instantaneously release said support member from said handle, and said adjusting screw being adjustable to vary the magnetic tripping point of the breaker while the thermal tripping point remains constant.

14. A circuit breaker comprising a switch member biased open and movable to open and close the circuit, an operating handle having a plurality of projections thereon and movable to effect opening and closing movements of said switch member, a support member having one end releasably supported on one of said projections and the other end pivotally supported on said switch member, a trip device operable in response to overload currents to engage and release said one end of said support member from said one projection to permit longitudinal movement of said support member and opening movement of said switch member, and longitudinal movement of said support member causing said one end thereof to engage another of said projections and actuate said handle to an indicating position.
